H. GESSLER,
OVERFLOW ALARM.
APPLICATION FILED MAY 3, 1922.

1,434,112.

Patented Oct. 31, 1922.

UNITED STATES PATENT OFFICE.

HARRY GESSLER, OF NEW YORK, N. Y.

OVERFLOW ALARM.

Application filed May 3, 1922. Serial No. 558,146.

To all whom it may concern:

Be it known that I, HARRY GESSLER, a citizen of the United States, residing at New York, in the county of New York and State 5 of New York, have invented certain new and useful Improvements in Overflow Alarms, of which the following is a specification.

This invention relates to alarms used to 10 indicate when the water level in a drip pan or similar receptacle has reached a predetermined level. As well known the overflow of a drip pan beneath an ice box causes considerable damage and also prevents the tidy 15 up-keep of such quarters.

Another object is the provision of a device as described which is controlled by a float and a means for adjusting the latter to suit 20 various conditions such as a larger or smaller sized drip pan or similar other reasons.

These and other objects will become apparent in the description below in which characters of reference refer to like-named parts in the drawing.

25 Referring briefly to the drawing; Figure 1 indicates a top plan view of the device showing cover member cut away so as to show the alarm actuating mechanism.

Figure 2 is a sectional front elevational 30 view taken on line 2—2 of Figure 1.

Figure 3 is a side elevational view of the device showing means for extending the float and means for securing the device to a receptacle.

35 Describing the drawing in detail the numeral 10 indicates a substantially square body plate which has the backs 11 of clamp jaws 12 formed integral therewith. Space 13 between the said jaws 12 receive the vertical wall 14 of whatever receptacle or drip pan is being used. A screw 15 threadable in 40 one of the jaws 12 rigidly secures the device to the above said wall 14 and prevents the same from being broken by falling or otherwise becoming inoperative.

An angular upstanding bracket 16 is secured to plate 10 has an arm 17 pivoted thereon, the latter extending horizontally out of the chamber formed by the casing 18. 45 Ears 19 projecting upwardly at the corners of body plate 10 receive the threaded ends of screws 20 which retain said casing 18 rigidly in place on the said plate 10.

An upper frame 21 and a lower 22 form means for journalling a vertical spindle 24 upon which a toothed wheel and a pinion 26 is mounted. The latter lies in mesh with a gear wheel 27 which is rotatably mounted on shaft 28 the latter having one end of a spiral spring 29 secured thereto while its 55 opposite end is fixed to the post 30. The usual ratchet wheel 31 and pawl 32 engaging the latter, are provided on the shaft 28 and a key 33 surmounting the said shaft provides a means for winding the spiral spring. 60

The said spindle 25 has pallet arms 34 which alternately engage the toothed wheel 23 and vibrate the extending arm 35. The latter is provided with a striker 36 which will contact the sound disk 37. 70

A locking lug 38 forming an extension of arm 17 engages the striker arm 35 when arm 17 is at its lowest position.

The end of said lever arm 17 pivotally receives a hollow rod 38 which is provided 75 with a longitudinal slot 39 having a series of semi-circular notches 40 cut on one side thereof.

A hollow spherical float 41 has a radially disposed stud 42 rigidly mounted thereon, 80 the latter being insertable in rod 38 and has a pin 43 projecting from the side which engages any of the notches 40 and retains the float in any of the adjusted positions.

In use the device is secured to a receptacle 85 by slipping the clamp jaws 12 over the wall and adjusting the members 15.

The float arm 38 is rotated to any angle desired depending on the level at which the alarm is to be given. Additional and finer 90 adjustment is accomplished by engaging any of the various notches 40.

As the level of the water rises the float 41 will be buoyed up by the pressure of the water, until the locking lug 38 is disengaged 95 from the striker bar 35 which permits the vibration of the striker head 36 against the surface of the sound disk 37 thus giving an audible signal that the liquid has risen to the predetermined level.

Turning the winding key 33 will retain the spiral spring 29 after the latter has been used.

I claim:—

A device of the class described comprising, 105 a body plate and casing member thereon, a

striker member in said casing, a disk mounted adjacent said striker, said disk adapted to give an audible alarm when the striker is vibrated, a lever arm pivoted in said casing having a locking lug engaging said striker when said lever is in lowermost position, a hollow rod pivoted at the end of

said lever, a float member, a stud thereon, said stud slidably in the hollow rod, means for vibrating said striker when the lever 10 arm is lifted and means for securing the device to a receptacle.

In witness whereof I affix my signature.

HARRY GESSLER.
